UNITED STATES PATENT OFFICE.

JACOB C. EICHHORN, OF DETROIT, MICHIGAN, ASSIGNOR TO THE VICTOR JAR CO., OF DETROIT, MICHIGAN, A CORPORATION OF MICHIGAN.

DESIGN FOR A JAR OR RECEPTACLE.

43,566.

Specification for Design.

Patented Feb. 18, 1913.

Application filed November 12, 1912. Serial No. 731,032. Term of patent 3½ years.

To all whom it may concern:

Be it known that I, JACOB C. EICHHORN, a citizen of the United States of America, residing at Detroit, in the county of Wayne and State of Michigan, have invented a certain new, original, and ornamental Design for Jars or Receptacles, of which the following is a specification, reference being had therein to the accompanying drawings forming part thereof.

Figure 1 is a side elevation of a jar show-

ing my new design. Fig. 2 is a vertical central section through the jar showing the interior optic finish.

I claim:—

The ornamental design for a jar or receptacle, as shown.

JACOB C. EICHHORN.
